UNITED STATES PATENT OFFICE.

WILLIAM SCHNELL, OF DETROIT, MICHIGAN, ASSIGNOR, BY MESNE ASSIGNMENTS, TO TERNSTEDT MANUFACTURING COMPANY, OF DETROIT, MICHIGAN, A CORPORATION OF MICHIGAN.

WINDOW-REGULATOR-HANDLE ASSEMBLY.

Application filed October 9, 1922. Serial No. 593,166.

This invention relates to a window regulator handle assembly. It has for its object an improvement in the mounting of the handle upon the escutcheon plate and an improvement in the attachment of the escutcheon plate to the regulator casing.

Heretofore there have been several ways of mounting the regulator handle on the operating shaft. The first way and possibly 10 the most obvious way, was to simply square the end of the operating shaft and pass the hub of the crank handle over the shaft and secure it in place by a set screw. This was, however, found to be crude and unsatisfactory.

Another way that has been quite extensively used and quite satisfactory, has been to attach the handle to the operating shaft by a split nut and groove assembly such as 20 shown and claimed in the Allmand Patent No. 1,278,552. This escutcheon plate in no way supports the handle, hence was not a bearing plate but simply a finishing plate to cover up the rough ends of the trimming. 25 This plate was simply held loosely between the nut and the trimming.

A third common way of mounting the handle has been to secure the escutcheon plate and hub of the handle together so that the 30 handle can rotate in the escutcheon plate but cannot be uncoupled therefrom. In order to couple the handle up with the operating shaft, it is then necessary to secure the escutcheon plate to the cover plate of the regulator by means of a plurality of screws. 35 These screws have their heads exposed and consequently mar the appearance of the internal fittings of the car.

It is the object of the present invention to 40 provide an escutcheon plate which is also a bearing plate in which the handle is rotatably supported and at the same time afford an attachment between the escutcheon plate and the regulator casing which is entirely concealed and wholly eliminates the screws.

In the drawings:

Fig. 1 is an elevation of the window regulator showing the pressed metal cover plate in position.

50 Fig. 2 is a section taken on the line 2—2 of Fig. 1.

Fig. 3 is a sectional detail showing the parts by which the escutcheon plate is held in place.

Fig. 4 is a detail of a modified form of ferrule.

Fig. 4^A is a detail of the modified form of escutcheon plate boss.

Fig. 5 is a cross section showing the modified form securing the escutcheon to the cover plate.

Fig. 6 is an elevation of the inside of a closed car showing the escutcheon plate.

Fig. 7 is an enlarged elevation of the same.

The regulator parts will be apparent from 65 an inspection of the drawing; no claim is made to any particular form of regulator. The regulator here shown has a chain lift, the chain being designated *a*; on this is a lifting pin *b* which connects with the window in a familiar way so that the window rises and falls with the movement of the chain. The chain runs over a lower sprocket wheel *d* and an upper sprocket wheel *e*. The 70 sprocket wheel is driven through the gears *f*, *g* and *h*. The driving pinion *h* is driven through a clutch contained in the housing *i* and which need not be detailed here as the same is no part of the invention. The operating parts are enclosed by a pressed metal 75 cover plate *j* which is secured to the main supporting plate *k* by the screws *m*.

A ferrule *n* either internally screw threaded as shown in Fig. 3, or provided with the equivalent construction, a bayonet slot as 85 shown in Figs. 4 and 5, is used. The cover plate is provided with a ring boss *o* and a punched hole *p* with key lugs *q* punched out. The ferrule is provided with key slots *r* adapted to fit over these key lugs to prevent 90 the ferrule from turning. The bottom of the ferrule is provided with a ring boss *s* which fits into the perforation punched in the cover plate. The flanged brass bushing *t* is then fitted into the ferrule as shown in Fig. 2 95 and the outer end riveted over as at *u*. This securely locks the ferrule to the cover plate and constitutes, in a broad sense, an anchor for the ferrule.

The escutcheon plate is designated *w* and 100 may also be termed the bearing plate as it rotatably supports the crank handle. The crank handle *x* is provided with a hub *y* that fits over the squared end *z* of the operating shaft which connects with the clutch contained in the case *i*. This escutcheon or bearing plate may be united or locked on to 105 the hub of the crank handle so that the hub

can rotate therein in several ways. The end of the hub can be up-set by suitable dies or the escutcheon plate can be cast directly on to the hub of the handle by using a graphite film over the hub of the crank handle. The escutcheon plate is provided with an outer annular boss 1 and an inner annular boss 2, the latter externally screw threaded.

The poor panel is ordinarily trimmed with a heavy card-board base 3 over which is drawn the trimming material 4 which may be a mohair, plush, velour, or other relatively deep and yieldable material. By having the bayonet joint parts or screw threads on the inside of the ferrule the trimming material will not get into the threads or be torn thereby.

The main supporting plate of the regulator is secured to the lock board in a familiar way. The trimming for the door or body is then secured over the lock board and the regulator cover, exposing only the ferrule. Only a small hole is necessary to permit the ferrule to protrude through the trimming, no allowance has to be made to permit screws or other fastening device to pass through the trimming material. The handle may then be very easily mounted on to the door or connected with the regulator by simply screwing the escutcheon or bearing plate into the ferrule. This may be done with the fingers; as the plate is screwed down it will press into the soft trimming material which will constitute a very good lock nut to lock the plate in place.

In the claims I have referred to the threads and the bayonet joint generically as parts of locking devices which detachably engage.

It will be obvious that the invention here described has a wider application than window regulators, and hence I do not wish to be limited to window regulator parts except where these are expressly referred to in the claims.

What I claim is:

1. In a window regulator, the combination of a casing provided with window regulator operating parts, a shaft protruding from said casing, a member anchored directly to said casing, a bearing and escutcheon plate that can be detachably coupled-up with said member by relative rotation and longitudinal movement, and a crank handle rotatably supported in said bearing plate and coupled up with said shaft when the bearing plate has been coupled up to the said member.

2. In a window regulator, the combination of a casing provided with window regulator operating parts, a shaft protruding from said casing, trimming material drawn over said casing and perforated to allow said shaft to pass through, a member terminating at its inner end on the exterior of the casing, and anchored by the side wall of said casing,

a bearing and escutcheon plate that can be detachably coupled up with said member by relative longitudinal and rotative movement, the said trimming when engaged by the longitudinal movement of the bearing plate serving to secure the same against uncoupling rotative movement, and a crank handle rotatably supported in said bearing plate and coupled up with said shaft when the bearing plate has been coupled up to the said member.

3. In a window regulator, the combination of a casing provided with window regulator operating parts, a shaft protruding from said casing, a ferrule located wholly on the outside of the casing and anchored to the side wall of said casing said ferrule surrounding said shaft and provided with parts of locking devices and a bearing plate and crank coupled together to permit rotation, said bearing plate provided with parts of locking devices adapted to detachably engage with the parts of locking devices on the ferrule to detachably connect the bearing plate to the ferrule, the said crank being provided with a hub adapted to couple up with said shaft, when the bearing plate is secured to the ferrule.

4. In a window regulator, the combination of a casing provided with window regulator operating parts, an operating shaft having a non-circular end, a ferrule located on the outside of the casing and having the inner end anchored to the side wall of said casing and provided with parts of locking devices, and a bearing plate and crank handle with the hub of the crank handle coupled up with the bearing plate to permit rotation of the handle in the bearing plate, said bearing plate being provided with an inwardly projecting portion having parts of locking devices adapted to engage with said parts of locking devices on the ferrule to detachably secure the bearing plate in place, the hub of the crank handle being provided with an opening adapted to fit over the non-circular end of the operating shaft.

5. In an operating device, the combination of a casing for housing the operating parts, and having an opening punched therein, an operating shaft projecting therefrom, a ferrule surrounding the projecting end of the operating shaft and the opening punched in the casing, a bushing riveting the ferrule to the casing, said ferrule being provided with parts of locking devices and a bearing plate provided with an inwardly projecting portion having parts of locking devices adapted to detachably engage the parts of locking devices on the ferrule, and a crank handle provided with a hub coupled up with the bearing plate and rotatable thereon, said hub coupling up with the operating shaft when the bearing plate is locked onto the ferrule.

6. In an operating device, the combination

of a casing for enclosing the operating parts, a shaft projecting from the casing, a ferrule provided with key slots, the said casing provided with key lugs engaging the key slots to prevent rotation of the ferrule, a bushing riveting the ferrule to the casing, the said ferrule being provided with parts of locking devices, and a handle assembly in the form of a bearing plate having parts of locking devices arranged to detachably engage the parts of locking devices on the ferrule and a crank handle provided with a hub united with the bearing plate and rotatable therein, said hub arranged to couple with the operating shaft when the bearing plate is secured to the ferrule.

7. In an operating device, the combination of a casing containing window regulator operating parts, a ferrule having its inner end anchored to the side wall of the casing and provided with internal screw threads, a bearing plate having an inwardly projecting annular boss, externally threaded for screwing into the internal threads of the ferrule, an operating shaft projecting from the casing on the inside of the ferrule, a crank handle having a hub locked into the bearing plate and rotatable therein and provided with an opening arranged to removably fit over the end of the operating shaft.

8. In a window regulator, the combination of a casing, window regulator operating parts contained in said casing, a member attached to said casing, a bearing and escutcheon plate which can be detachably coupled up with said member by relative rotational and longitudinal movement, a shaft and crank handle for coupling together, one of which latter two elements is rotatably supported in the bearing and escutcheon plate and both of which are operatively connected with the window regulator parts when the bearing and escutcheon plate are connected up with the said member.

45 9. In a window regulator, the combination of a casing provided with window regulator operating parts, a shaft for connection with said parts, a ferrule located on the outside of the casing and anchored to the side wall of said casing, said ferrule surrounding said shaft and provided with parts of locking devices, a crank arranged to be coupled to said shaft, a bearing plate in which one of the latter two elements is rotatably supported, said bearing plate provided with parts of locking devices adapted to detachably engage with the parts of locking devices on the ferrule, to detachably connect the bearing plate to the ferrule, and thereby form an operative connection between the crank and the operating parts.

10. The combination with a body trimmed on the inside by a trimming material having an opening therethrough and supporting on a wall thereof an operating mechanism hav-

ing a plate provided with interlocking means thereon and having an actuating part in registry with the opening through said trimming, of a handle assembly comprising an escutcheon having a portion that registers with the opening in the trimming and detachably turns into said interlocking means to be thereby supported in fixed relation to said plate, said escutcheon having another portion that bears against the said trimming and conceals the opening therethrough and forms a shield and retainer frame for any raw edge about said opening, said escutcheon also forming a journal bearing, a handle having a crank or lever portion and a hub portion integrally connected together, the latter rotatably supported in the journal bearing of the escutcheon but restrained from longitudinal movement and detachment, a member on the hub of diameter larger than the hub and located behind the escutcheon to prevent such detachment, said hub and actuating part having interfitting portions that automatically couple together in driving relation when the escutcheon portion is turned into the interlocking means on the plate, the said members being provided with yielding means between the escutcheon and the plate to restrain the escutcheon part turning out of the said interlocking means.

11. The combination with a body trimmed on the inside by a trimming material having an opening therethrough and supporting on a wall thereof an operating mechanism having a plate provided with a threaded ferrule thereon and having an actuating part in registry with the opening through said trimming, of a handle assembly comprising an escutcheon having a portion that registers with the opening in the trimming and detachably screws upon said ferrule to be thereby supported in fixed relation to said plate, said escutcheon having another portion that bears against the said trimming and conceals the opening therethrough and forms a shield and retainer frame for any raw edges about said opening, said escutcheon also forming a journal bearing, a handle having a crank or lever portion and a hub portion integrally connected together, the latter rotatably supported in the journal bearing of the escutcheon but restrained from longitudinal movement and detachment from said bearing by an enlargement of the hub concealed behind said escutcheon, the said hub and actuating part having interfitting portions that automatically couple together in driving relation when the escutcheon portion is screwed into the ferrule on the plate, the said members being provided with yielding means between the escutcheon and the plate to restrain the escutcheon part turning out of the said ferrule.

12. The combination with a body trimmed

on the inside by a trimming material having an opening therethrough and supporting on a wall thereof an operating mechanism having a plate provided with interlocking means thereon and having an actuating part in registry with the opening through said trimming, of a handle assembly comprising an escutcheon having a portion that registers with the opening in the trimming and detachably turns into said interlocking means 70 to be thereby supported in fixed relation to said plate, said escutcheon having another portion that bears against the said trimming and conceals the opening therethrough and 75 10 15 forms a shield and retainer frame for any raw edge about said opening, said escutcheon also forming a journal bearing, a handle having a crank or lever portion and a hub portion integrally connected together, the latter rotatably supported in the journal bearing of the escutcheon but restrained from longitudinal movement and detachment, a member on the hub of diameter larger than the hub and located behind the 80 85 90 20 25 30 35 40 45 50 55 60 65 70 75 80 85 90 95 100 105 110 115 120 125 130 escutcheon to prevent such detachment, the said hub and actuating part having interfitting portions that automatically couple together in driving relation when the escutcheon portion is turned into the interlocking means on the plate.

13. The combination with a body trimmed on the inside by a trimming material having an opening therethrough and supporting on a wall thereof an operating mechanism having a plate provided with a threaded ferrule thereon and having an actuating part in registry with the opening through said trimming, of a handle assembly comprising an escutcheon having a portion that registers with the opening in the trimming and detachably screws upon said ferrule to be thereby supported in fixed relation to said plate, said escutcheon having another portion that bears against the said trimming and conceals the opening therethrough and forms a shield and retainer frame for any raw edges about said opening, said escutcheon also forming a journal bearing, a handle having a crank or lever portion and a hub portion connected together, the latter rotatably supported in the journal bearing of the escutcheon but restrained from longitudinal movement and detachment from said bearing by an enlargement of the hub concealed behind said escutcheon, the said hub and actuating part having interfitting portions that automatically couple together in driving relation when the escutcheon portion is screwed into the ferrule on the plate.

14. The combination with a body trimmed on the inside by a trimming material having an opening therethrough and supporting on a wall thereof an operating mechanism having a plate provided with interlocking means

thereon and having an actuating part in registry with the opening through said trimming, of a handle assembly comprising an escutcheon having a portion that registers with the opening in the trimming and detachably turns into said interlocking means to be thereby supported in fixed relation to said plate, said escutcheon having another portion that bears against the said trimming and conceals the opening therethrough and forms a shield and retainer frame for any raw edge about said opening, said escutcheon also forming a journal bearing, a handle having a crank or lever portion and a hub portion connected together, the latter rotatably supported in the journal bearing of the escutcheon but restrained from longitudinal movement and detachment, a member on the hub of diameter larger than the hub and located behind the escutcheon to prevent such detachment, the said hub and actuating part having interfitting portions that automatically couple together in driving relation when the escutcheon portion is turned into the interlocking means on the plate.

15. The combination with a body trimmed on the inside by a trimming material having an opening therethrough and supporting on a wall thereof an operating mechanism having a plate provided with a threaded ferrule thereon and having an actuating part in registry with the opening through said trimming, of a handle assembly comprising an escutcheon having a portion that registers with the opening in the trimming and detachably screws upon said ferrule to be thereby supported in fixed relation to said plate, said escutcheon having another portion that bears against the said trimming and conceals the opening therethrough and forms a shield and retainer frame for any raw edges about said opening, said escutcheon also forming a journal bearing, a handle having a crank or lever portion and a hub portion connected together, the latter rotatably supported in the journal bearing of the escutcheon but restrained from longitudinal movement and detachment from said bearing by an enlargement of the hub concealed behind said escutcheon, the said hub and actuating part having interfitting portions that automatically couple together in driving relation when the escutcheon portion is screwed into the ferrule on the plate.

16. The combination with a body supporting on the wall thereof an operating mechanism having a plate provided with interlocking means thereon and having an actuating part, of a handle assembly comprising a bearing that detachably turns into said interlocking means to be thereby supported in fixed relation with said plate, said bearing forming a journal support, a handle having a crank or lever and hub portion integrally connected together, the latter rotatably sup-

ported in the journal bearing but restrained from longitudinal movement and detachment, a member on the hub of diameter larger than the hub and located behind the bearing to prevent such detachment, the said hub and actuating part having interfitting portions that automatically couple together in driving relation when the bearing is turned into the interlocking means on the plate.

17. The combination with a body supporting on the wall thereof an operating mechanism having a plate provided with interlocking means thereon, and having an actuating part, of a handle assembly comprising a bearing that detachably turns into said interlocking means to be thereby supported

in fixed relation with said plate, said bearing forming a journal support, a handle having a crank or lever and a hub portion united to rotate together and against separation longitudinally, the said hub rotatably supported in the journal bearing but restrained from longitudinal movement and detachment, a member on the hub of diameter larger than the hub and located behind the bearing to prevent such detachment, the said hub and actuating part having interfitting portions that automatically couple together in driving relation when the bearing is turned into the interlocking means on the plate.

In testimony whereof I affix my signature.

WILLIAM SCHNELL.
